(57) **CLAIM**

The ornamental design for firearm with off-trigger locator, as shown and described.

DESCRIPTION

FIG. 1 is a partial right side elevational view of a firearm with off-trigger locator of our new design comprising an elongate raised portion disposed on a frame of the firearm adjacent the trigger of the firearm;

FIG. 2 is a partial left side elevational view of the firearm of FIG. 1;

FIG. 3 is a partial perspective view of the firearm of FIG. 1;

FIG. 4 is a partial alternate perspective view of the firearm of FIG. 1;

FIG. 5 is a partial alternate perspective view of the firearm of FIG. 1;

FIG. 6 is a partial alternate perspective view of the firearm of FIG. 1;

FIG. 7 is an enlarged partial cross-section view of the firearm of FIG. 1 taken along lines 7-7 of FIG. 1;

FIG. 8 is a partial left side elevational view of a firearm showing an alternate embodiment of a firearm with off-trigger locator of our new design comprising an elongate raised portion disposed on a frame of the firearm adjacent the trigger of the firearm;

FIG. 9 is a partial right side elevational view of the firearm of FIG. 8;

FIG. 10 is a partial perspective view of the firearm of FIG. 8;

FIG. 11 is a partial alternate perspective view of the firearm of FIG. 8;

FIG. 12 is a partial perspective view of the firearm of FIG. 8;

FIG. 13 is a partial alternate perspective view of the firearm of FIG. 8;

FIG. 14 is an enlarged partial cross-section view of the firearm of FIG. 8 taken along lines 14-14 of FIG. 8;

FIG. 15 is a partial right side elevational view of a firearm showing an alternate embodiment of a firearm with off-trigger locator of our new design comprising an elongate raised portion disposed on a frame of the firearm adjacent the trigger of the firearm;

FIG. 16 is a partial left side elevational view of the firearm of FIG. 15;

FIG. 17 is a partial alternate perspective view of the firearm of FIG. 15;

FIG. 18 is a partial alternate perspective view of the firearm of FIG. 15;

FIG. 19 is a partial alternate perspective view of the firearm of FIG. 15;

FIG. 20 is a partial alternate perspective view of the firearm of FIG. 15; and,

FIG. 21 is an enlarged partial cross-section view of the firearm of FIG. 15 taken along lines 21-21 of FIG. 15.

The dashed lines within the figures are for illustrative purposes only and form no part of the claimed design.
